UNITED STATES PATENT OFFICE

2,540,060

HAMMER TOY

Elmer Szantay, Chicago, Ill., assignor to Sandee Manufacturing Company, a corporation of Illinois

Application February 28, 1949, Serial No. 78,856

1 Claim. (Cl. 46—1)

1
This invention is directed to toys for children. The principal object of this invention is to provide a hammer toy which is simple in construction, which is inexpensive to manufacture, which readily appeals to small children, which is safe to play with, and which will not break or crack or splinter as a result of rough handling.

Briefly, the hammer toy of this invention includes a base, an inverted U-shaped guide carried by the base, a ball carried by the guide and a lever fulcrumed on the base for propelling the ball from one side of the guide to the other as the ends of the lever are alternately hammered. The hammer toy of this invention appeals greatly to small children and teaches them muscular co-ordination in the manipulation thereof.

Other objects of this invention reside in the details of construction of the hammer toy and the cooperative relationship between the component parts thereof.

Further objects and advantages will become apparent to those skilled in the art upon reference to the accompanying specification, claim and drawing in which:

Figure 1 is a sectional view of a hammer which may be utilized for manipulating the toy;

Figure 2 is a top plan view of the hammer toy of this invention;

Figure 3 is a vertical sectional view through the hammer toy, and

Figure 4 is a sectional view taken along the line 4—4 of Fig. 2.

Referring to Figs. 2 and 3, the hammer toy of this invention includes a base 10 which is preferably circular in configuration. It is preferably made of substantially unbreakable thermo-plastic and may be formed by injection molding. The center of the base 10 is provided with an opening 11 for receiving the shank 12 of a fulcrum 13 having a rounded head. The fulcrum is also preferably formed of substantially unbreakable thermo-plastic and may be formed by injection molding. The fulcrum may be held in the base 10 by a pressed fit or may be suitably cemented therein.

The base 10 is also provided with a pair of diametrically opposite holes 14 for receiving the legs 16 of an inverted U-shaped guide 15. The guide 15 is preferably made of substantially unbreakable thermo-plastic and it may be formed by suitably bending an extrusion molded rod. After the legs 16 of the U-shaped guide are inserted in the openings 14 they are preferably swaged over at 17 for maintaining the U-shaped guide on the base 10.

2

A lever 18 engages and is fulcrumed upon the fulcrum 13, and is provided with a pair of holes 19 for receiving the legs 16 of the inverted U-shaped guide 15. The holes 19 cooperate with the legs 16 for maintaining the lever 18 in place on the fulcrum 13. The lever 18 is preferably made of substantially unbreakable thermo-plastic and may be formed by extrusion molding. To reduce weight and cost, the lever 18 is preferably hollow as indicated in Figs. 3 and 4.

The inverted U-shaped guide 15 carries a ball 20 provided with holes 21 for receiving the U-shaped guide. The ball 20 is preferably hollow and is preferably formed of substantially unbreakable thermo-plastic. In forming the ball, it is preferably made in two injected molded halves and then suitably secured together as by cementing.

The hammer toy may be operated by a hammer as illustrated in Fig. 1. The hammer includes a head 22 preferably made from substantially unbreakable thermo-plastic. The hammer may be formed from two substantially semi-cylindrical injection molded members suitably secured together with cement. The hammer head is provided with an opening 23 for receiving a rod 24 which may be held in place in the hammer head by a forced fit or by cementing. The rod 24 may be formed from substantially unbreakable thermo-plastic by extrusion molding. The other end of the rod 24 is provided with a hole 25 for receiving the ends of a handle 26 also formed of substantially unbreakable thermo-plastic. The end of the rod 24 is covered with a ball 27 provided with holes 28 for receiving the handle 26. The ball 27 is preferably formed by injection molding substantially unbreakable thermo-plastic. The hammer head 22 being hollow may be provided with suitable pellets 29 so that it may simulate a rattle and further add to its appeal to children.

Any suitable substantially unbreakable thermo-plastic may be utilized in the manufacture of the toy and hammer, such as cellulose acetate butyrate.

In the operation of the toy, the lever 18 and ball 20 are located in the position shown in Fig. 3. The raised end of the lever 18 is then struck with the hammer head 22 whereupon the ball 20 is propelled from one leg 16 of the inverted U-shaped guide 15 to the other leg 12 and the parts then assume a position as shown in broken lines in Fig. 3. To return the ball 20 to the original position the other end of the lever 18 is then struck with the hammer 22. Thus, the ball

20 may be propelled from one leg of the guide to the other leg as the extending ends of the lever 18 are alternately hammered.

The hammer toy of this invention appeals greatly to small children and teaches them muscular coordination in the operation thereof. The hammer toy is simple in construction, it may be inexpensively manufactured, it is safe for small children to play with, and it will not break or crack or splinter as a result of rough handling. 10

While for purposes of illustration, one form of this invention has been disclosed, other forms thereof will become apparent to those skilled in the art upon reference to this disclosure, and therefore, this invention is to be limited only by the scope of the appended claim.

I claim as my invention:

A hammer toy comprising a base, an inverted U-shaped guide having its legs carried by the base, a fulcrum carried by the base between the legs of the guide, a lever freely resting upon the fulcrum and provided with a pair of holes for receiving the guide legs and extending beyond the 20

guide legs in both directions whereby the lever is pivotally supported on the fulcrum and guided by the guide legs, and a ball slidably carried by the guide above the lever and adapted to be propelled from one leg of the guide to the other as the extending ends of the lever are alternately hammered.

ELMER SZANTAY.
